UNITED STATES PATENT OFFICE.

ISAAC E. PALMER, OF MIDDLETOWN, CONNECTICUT.

PROCESS OF CONDITIONING TEXTILE MATERIAL.

1,033,926.

Specification of Letters Patent. Patented July 30, 1912.

Application filed July 17, 1909. Serial No. 508,165.

To all whom it may concern:

Be it known that I, ISAAC E. PALMER, a citizen of the United States, and a resident of Middletown, in the county of Middlesex 5 and State of Connecticut, have invented an Improvement in Processes of Conditioning Textile Material, of which the following description, in connection with the accompanying drawings, is a specification, like 10 letters on the drawings representing like parts.

This invention relates to the process of conditioning textile material with a treating liquor which is preferably a bleaching liquor or other liquor involving the chemical treatment of the material and preferably involving the continued treatment of the material by an absorbed portion of the liquor after the material has been separated 20 from the body of the material.

In order that the principles of the invention may be readily understood, I have disclosed a form of apparatus embodying the same in the accompanying drawing, where- 25 in—

Figure 1 is a diagrammatic plan view of an apparatus for practising my invention; Fig. 2 is a vertical section of one form of time receiver; Fig. 3 is a vertical section 30 of another form of time receiver; Fig. 4 is a diagrammatic representation illustrating the manner of use of the saturating receptacle and so-called time receivers; Fig. 5 is a view partially in side elevation and 35 partially in vertical section of a receptacle preferably employed in the practice of my invention; and Figs. 6 to 10 inclusive are diagrams illustrating certain manners of use of the apparatus herein disclosed.

The apparatus herein disclosed is intended for use in treating textile material in a woven condition or unwoven condition in which latter case the material may be subjected to treatment as a warp chain or otherwise. The material whatever be its condition and whatever be its nature is passed through the apparatus in band form with the same end always foremost, the material being passed successively from one 40 vat receiver or receptacle to another in any suitable manner. Preferably the material is subjected to a preliminary washing or boiling operation followed if desired by a cooling operation, after which the material 45 is subjected to treatment in a saturation receptacle by a liquor of suitable nature, and

which is preferably a bleaching liquor. After subjecting the material for the desired length of time to treatment in the bleaching liquor, the material is withdrawn 60 from the receptacle containing such liquor and a portion of the liquor is preferably expelled from the material. In this condition; that is, either saturated or wetted to a degree less than saturation, the material is conveyed to what I am pleased to term a time or storage receiver, through which the material passes while permitting the continued action upon the material of the residual liquor absorbed thereby, and thus 70 conveyed from the saturation receptacle to the time receiver. If the material has not been sufficiently treated by the residual absorbed liquor when the material issues from the first time receiver, the material is there- 75 upon conveyed through a second or any number of succeeding time receivers.

The prolonged action of a strong bleaching or other liquor upon the goods is injurious, and the short action of a strong 80 liquor is ineffective. By subjecting the goods to the prolonged action of a weak liquor, I am enabled to get the best results. Therefore, I may employ a weak treating liquor to which I subject the goods, but 85 preferably I use a liquor of substantially normal strength to the action of which the goods are subjected as they are being drawn through the saturation receptacle. As the goods are being withdrawn from 90 such receptacle, I expel a very considerable proportion of the treating liquor, preferably by squeeze rolls, and then permit the liquor remaining in the goods to act there- 95 on in the next succeeding receiver or receivers, and preferably until the said liquor has fully exhausted itself. In this way I get the gentle, beneficial effect of the prolonged action of a weak treating liquor. The action of the liquid remaining in the 100 goods after passing them through squeeze rolls, is permitted to continue without subjecting the goods to the action of any other liquid or fluid, unless it may be necessary suddenly to terminate the bleaching or 105 treating action, which I effect by flooding the goods with water or other suitable liquid.

Immediately upon the termination of the action of the bleaching or other treating 110 liquor, whether this action terminate with the first or any succeeding time receiver, the

material is thereupon washed and is thereafter preferably soured and subjected to a final washing. As disclosed hereinafter, I have provided means whereby the bleaching or other treating action may be terminated at any desired point or period. Preferably, I accomplish this result by providing means whereby the material may be flooded with water at the necessary time and point, whether this be in the saturation receptacle or in one or another of the time receivers. I have also provided means for conveying the material continuously through the apparatus at a speed which may be varied to suit the strength of the treating liquor and the weight of the goods being treated, or, in other words, the speed may be varied to conform to the effectiveness of the action of the treating liquor. As the material is withdrawn from the saturation receptacle, preferably I forcibly expel a portion of the liquor from the material by squeeze rolls or otherwise so that the material is delivered or conveyed to a time receiver in a condition of wetness less than saturation, although I may retain any desired portion or all of the absorbed treating liquor in the material as it is conveyed to the time receiver or receivers. As previously set forth, I preferably expel a very considerable proportion of the bleaching or other treating liquor as the material is withdrawn from the saturation receptacle, so as to get the beneficial effect of the prolonged action of a weak liquor. The number of time receivers employed is determined by their size or time required for bleaching or other treatment, and the quantity of goods subjected to such treatment. Any suitable bleaching liquor may be employed. Any suitable souring or acid wash may be employed, but preferably I use oil of vitriol or sulfuric acid.

As will be more fully disclosed herein-after, I may use one of the time receivers for purposes other than above referred to. For example, if the bleaching be terminated in the first time receiver, the material may be washed in the next time receiver and subjected to a souring action in a succeeding time receiver, and again washed in still another time receiver if desired.

Intermediate one or more of the time receivers or otherwise suitably arranged in the system, I preferably interpose a receptacle through which the material is passed in one direction. In such receptacle I introduce a liquid or liquids both at the point where the material is entered into the receptacle and at the point where the material issues therefrom, so that both the incoming and outgoing materials are subjected to the action of a fresh liquid. The two incoming liquid streams may be of the same nature or different. For example, both streams may

be water so that both the incoming and outgoing material may be subjected to fresh streams of water or one of the streams may be some suitable liquor, such for example as a souring liquor. Preferably in such case the souring liquor is introduced with the incoming material and the water is introduced to act upon the outgoing material. The stream introduced to act upon the outgoing material travels in a direction contrary to the outgoing material, and preferably the two streams commingle and are discharged together from the receptacle at a point intermediate the preferably upright ends thereof.

Referring more particularly to the drawings, the vat or receptacle into which the material is preferably first introduced is represented at 1 in Fig. 1, the material being delivered thereto in any suitable manner. In said receptacle the material is preliminarily washed or boiled. The material is conveyed through said vat by passing it about any desired number of rolls 2-2 driven in any suitable manner, as by a belt 3 from the shaft 4 provided with a cone 5, about which and the companion cone 6 is passed a belt 7. The cone 6 is fast upon a shaft 8 deriving power from any suitable source. By shifting the belt 7 upon the cone pulleys 5 and 6, the speed at which the material is conveyed through the apparatus may be varied for the purpose heretofore stated.

The material may be traversed from end to end of the vat in any suitable manner, and as it issues therefrom may be passed if desired through a suitable cooling vat 9 having one or more rolls 10 therein driven by belt 11 from the shaft 4, and wherein the material may be washed, or instead the material may be delivered directly to the saturation receptacle 12. The saturation receptacle is preferably provided with a bleaching liquor. This receptacle may be of any suitable construction, but preferably I employ the form of receptacle illustrated in Fig. 3.

In Fig. 1, I have represented three upright saturation receptacles 12 and 22, 22 into which the material is conveyed in succession. Two of these receptacles are represented in detail in Fig. 4. As shown in the latter figure the material issuing from either the boiling vat 1 or the cooling receptacle 9 preferably passes between squeeze rolls 13, and thence is directed to and about rolls 14 associated with which I preferably provide a traversing mechanism indicated in Fig. 1 at 14', whereby the material may be caused to move to and fro from end to end of the receptacle during its deposition therein. Preferably the material is folded as it is deposited in the receptacle and to that end I preferably provide a folder pivoted at 15 and having arms 16, 17 of unequal

length whereby the material may be folded into the first saturation receptacle in folds of alternating length. Beneath the folder is positioned the first saturation receptacle 12, herein represented as having upright receiving and discharge ends, the height of either of which may of course be varied to suit the exigencies to which the apparatus is adapted.

10 In Fig. 4, I have represented a pipe 19 for introducing the treating liquor, into the saturation receptacle 12. The rollers 14 are driven from the shaft 4 or otherwise in any suitable manner. After issuing from the 15 saturation receptacle 12, the material is then directed to and about the driven rolls 20 and is then by a folder 21 delivered into one end of the saturation receptacle 22 supplied with liquor by pipe 23. The material issuing 20 from the saturation receptacle 22 is thence conveyed if desired to a third receptacle of similar construction and nature indicated in Fig. 1, by suitable means. The rollers 20 are driven in suitable manner and have associated therewith suitable means to traverse 25 the material from end to end of the receptacles.

In Fig. 1, I have indicated at 24 means to traverse the material to and fro in the second and third saturation receptacles.

At 25 in Fig. 1 I have indicated mechanism connected by belt with the shaft 4, whereby the material may be traversed to and fro not only in the saturation receptacles but in the various succeeding time receivers.

A storage vat for the bleaching or other liquor is represented in Fig. 1 at 27, pipes 28 and 29 connecting this vat with the three 40 saturation receptacles indicated in Fig. 1. If desired, the several saturation receptacles there indicated may be positioned within a vat 30, into which the treating liquor may overflow from the saturation receptacles. I may, if desired, provide a pipe 31 connecting said vat and the supply vat 27 for returning the liquor to the latter, a pump 32 being provided if desired for this purpose.

50 The pipe 28 is represented in Fig. 1 as extending adjacent to the several time receivers, though not connected thereto, in order that if it be desired to employ any of said receivers primarily as saturation receptacles, proper connections from the liquor vat 27 may be made.

I preferably provide a pair of squeeze rolls or other liquor expelling means by which the desired proportion of the bleaching liquor is forcibly expelled from the material as the latter is withdrawn from the saturation receptacle and conveyed to the first time receiver. In the event that I employ a very weak solution of bleaching or 65 other treating liquor, I may in certain cases

deliver the goods unsqueezed, that is, in a fully saturated condition to the first time receiver to permit such weak solution to exhaust itself upon the goods in said first or in a succeeding time receiver, but preferably 70 and to secure the best results I forcibly expel a very considerable proportion of the treating liquid, as previously explained.

At 34, 35 and 36 in Fig. 1, I have represented vats, in each of which I position one or more so-called time receivers. In Fig. 1, I have represented each vat as containing two time receivers A A', B B' and C C' respectively, the material being delivered into and conveyed through said receivers in succession in substantially the manner that it was delivered into the saturation receptacle. Each of said receivers is provided with rollers for feeding or conveying the material therethrough and with suitable traversing means and folders for depositing the material in said receiver. The so-called time receivers or accumulators are receptacles wherein the material is deposited by gravity in loose folds and wherefrom the material is withdrawn for the subsequent operations.

The material is deposited in the time receivers and withdrawn therefrom with the same end always foremost, and the mass of material accumulating in each time receiver depends in amount and period upon the speed of the subsequent operations, such as the subsequent washing, souring or the like. In the said accumulators or time receivers, the action of the treating liquor 95 (such as a bleaching or dyeing liquor) may continue provided such liquor has not been entirely expelled from the material as it is drawn from the treating liquor vat or vats, or if the treating liquor has been entirely expelled from said material the latter merely accumulates in said time receivers.

The provision of said time receivers or accumulators is of extreme importance, as it permits the entire system of operations to be carried out in sequence, and if the subsequent washings, souring operations or the like cannot be carried on at a sufficiently rapid rate to take up constantly the material as fast as it is delivered from the saturation receptacles, the material can then accumulate in said time receiver or receivers. Although the material accumulates in said receivers, it is always withdrawn therefrom with the same end foremost, and 110 manual handling thereof is wholly avoided.

If the capacity of one time receiver or accumulator is insufficient, or for any reason it is desired to employ a plurality of time receivers or accumulators, it is evident that the material is led with the same end always foremost from one of said receptacles into another and is accumulated therein in loose folds as described. While said receivers may be of any suitable structure, I 125

have in Fig. 2 represented one of said receivers at 37. The material represented at 38 is delivered to the traversing mechanism and rolls 39 and thence past the folder 40 into the receiver 37, from which it issues at the lower end 41 and is redirected, as represented at 42 into the adjacent time receiver. The material is thus passed through any number of the time receivers, the number used for this purpose being dependent upon the time necessary to permit the required action of the bleaching or treating liquor upon the material. The liquor is preferably permitted to continue to act upon the material until it has exhausted itself. During such time the goods are not subjected to the action of any other fluid, unless it be necessary suddenly to terminate the action of the treating liquor, which is done by flooding the goods with water or other neutralizing liquor. If desired and as represented in Fig. 2, the discharge end of the several time receivers may be substantially horizontally directed and may be provided with idler 25 anti-friction rolls 43 to assist the delivery of the material from the receiver. From the last time receiver of the series the material is conveyed to a washing vat represented in Fig. 2 at 44. This vat is provided with suitable rolls to convey the material therethrough and is preferably equipped with squeeze rolls 45, between which the material issues from the vat.

In Fig. 5, I have diagrammatically represented a saturation receptacle *a* and time receivers *b*, *c* and *d* respectively, the material being conveyed continuously through said several receptacles and receivers in the manner already described. Preferably I do not employ squeeze rolls in conjunction with the time receivers *b*, *c* and *d*, nor with those indicated in Fig. 1, using them only in conjunction with the saturation receptacle or receptacles, unless one of the time receivers be used for washing or souring, as herein-after specified.

In Fig. 3, I have represented a casing or receptacle 50 which may be interposed at any desired point in the system herein described and is indicated clearly in diagrams hereinafter referred to. The entering material is represented in said figure at 51, it passing about the rolls 52 and being delivered by the folder 53 as previously described into the adjacent upright end 54 thereof. The material is discharged or drawn from the opposite end 55 and is thence directed between the squeeze rolls 56 and then to the same rolls 52 or to other similar rolls to be conveyed to the next similar vat or receptacle, if a plurality thereof be employed. A stream of liquid is entered by pipe 57 into the end 54 of the vat or receptacle, and another stream of liquid is entered by pipe 58 into the opposite end 55

of said receptacle. In this manner both the incoming and the outgoing portions of the material encounter or are subjected to fresh streams of liquid. I may introduce the same liquid, as for example water, into the pipes 57 and 58 or may introduce different liquids thereat. For example, I may introduce a souring liquor and in some cases a bleaching liquid by one or both of said pipes. I may also and preferably introduce a souring liquid by one of said pipes and water by another of said pipes. Thus, by the same receptacle the material may be subjected both to a souring action and to a subsequent washing action.

In Fig. 3, I have represented a second pipe 57', so that either of two different liquids may be entered into the end 54 of the receptacle. Similarly I may provide a second pipe adjacent the pipe 58 for the same purpose. The streams of liquid entering through the opposite ends of the receptacle are preferably provided with a common outlet intermediate said ends. Herein I have represented the receptacle as provided with an outlet 59 having a grating or perforated covering conforming to the general curvature of the casing or receptacle.

I contemplate the introduction of a flooding or neutralizing liquor into the system or apparatus so as to stop the bleaching or other action at any desired point. For that purpose, I contemplate discharging water into either the saturation receptacle or into one of the time receivers. In Fig. 1, I have represented a water tank 61, from which leads a pipe 62 extending to points adjacent the several saturation receptacles and time receivers. At any desired point, I may extend branch pipes so that water may be flooded into said receptacles and receivers. For example, in Fig. 4, I have represented a branch pipe 63 for discharging water into the saturation receptacle 22, and if desired similar means may be provided to discharge flooding water into the saturation receptacle 18. In Fig. 2, I have represented a branch pipe 64 for discharging water for this purpose into the upper end of a time receiver 37. Preferably each of said time receivers is thus equipped. As represented in Fig. 1, I provide a pipe 65 which may be connected with the several time receivers, or a vat wherein each of them is positioned so that the flooding water if used may be returned by pump 66 to the tank 61. After passing the material through the several time receivers as represented in Fig. 1, it is then directed to and passed through a washing vat 67 provided with a suitable number of driven rolls 68, after which it is directed through a vat or vats 69 and 70, whereby it is subjected to a souring or acid wash, the said vats 69 and 70 being provided with suitable driven rolls. The material is finally

discharged as indicated at 71 upon completion of the process.

As previously stated, the receptacle or vat 50 shown in Fig. 3 may be interposed if 5 and where desired in the system, and so if desired one or more of the time receivers may be employed for washing or for souring or for both steps depending upon the requirements of the particular case.

10 In Figs. 6 to 10, I have represented different ways of connecting up and using the several parts of the apparatus or system described. It will be understood, however, that the several units or parts of the apparatus or system may be otherwise combined 15 in any desired manner to direct the material therethrough. In Fig. 6, I have represented the material as passing through the boiling vat and from thence into a washing vat 20 and then into the saturation receptacle, from which it is delivered into the first time receiver acting as such. From this point, the material is delivered into the receptacle 50, into which water is introduced at both 25 ends for washing. From this point the material is delivered into the second time receiver, herein used for souring, and then into the third time receiver herein used for 30 washing. In the diagram shown in Fig. 7, the material, after issuing from the saturation receptacle, passes direct to the receptacle 50, whereinto water is introduced at both ends. The material is then passed to a time receiver, herein represented as used 35 for souring, and to another time receiver, herein represented as used for washing. In the diagram represented in Fig. 8, the material passes from the saturation receptacle into the receptacle 50, whereinto water is introduced 40 at one end and a souring liquid at the other end. From such receptacle the material is delivered into a time receiver used for washing. In the diagram shown in Fig. 9, the material passes from the saturation receptacle into a time receiver used as 45 such, thence into a second time receiver used for washing, and thence into the receptacle 50 in which a souring liquor is introduced at one end and water for washing at the opposite end. In the diagram illustrated in 50 Fig. 10, the material is passed from the saturation receptacle into a time receiver used as such, thence into a second time receiver used for washing, thence into the receptacle 50, whereinto two streams of souring liquor are introduced at opposite ends, whereafter 55 the material is directed into another time receiver used for washing.

The receptacle 50 is of general application and may be used not only in the several ways indicated, but may also be used as a saturation receptacle, in which case the bleaching or treating liquor is introduced at both ends to act upon the incoming and outgoing material. It will be noted that the

several receptacles and receivers are provided with upstanding ends, or with at least one upstanding end, and that the material is delivered by power driven means through the various receptacles and receivers always 70 with the same end foremost. Wherever the treating or bleaching action is terminated the washing action is immediately commenced, so that the washing action may commence in one of the time receivers or in a receptacle subsequent thereto. It will also be understood that in the time receivers I may wash, sour and again wash the materials, provided the bleaching action has been previously terminated. In such case I provide squeezing 75 rolls to act upon the material as it is discharged from the time receivers, then serving for washing, souring and washing. Generally speaking, the receptacle 50 is or may be employed at the point where the 80 bleaching is stopped, and in such case water is introduced thereinto at the receiving end thereof at least. It will further be understood that no treating liquor is introduced into the time receiver or receivers when used 85 as such, excepting the liquor that is carried thereinto by the goods from the saturation receptacle, which treating liquor is merely that remaining in the goods after they have been subjected to the action of the squeeze 90 rolls, as previously described.

The apparatus herein disclosed is not claimed in this application, as it is made the subject-matter of my co-pending application Serial No. 507,952, filed July 16, 1909. 100

The subject-matter of the present application is the herein described process for treating the material consisting substantially in saturating the material in a treating liquor, then separating the saturated 105 material and the unabsorbed body of said liquor while maintaining the material in a saturated or partially saturated condition by the absorbed liquor and then permitting the continued action upon said material of 110 the absorbed liquor of saturation, while excluding the material from liquor treatment otherwise than by said absorbed liquor of saturation. The subject-matter herein claimed further consists in the herein described method for terminating the action of the treating liquor by flooding it with a neutralizing liquor and also the process of 115 conditioning textile material consisting in passing the same through a liquid vat and subjecting both the incoming and outgoing portions of the material to the action of 120 fresh, incoming liquid streams.

Having thus described one illustrative embodiment of my invention, I desire it to 125 be understood that although specific terms are employed, they are used in a generic and descriptive sense and not for purposes of limitation, the scope of the invention being set forth in the following claims. 130

Claims:

1. That method of continuously conditioning textile material in lengths which consists in progressing the material with the same end always foremost and subjecting it during said progress to a washing action, then depositing a mass of said material in successive folds and substantially saturating it with a treating liquid, then withdrawing 5 said folds from said mass in their order of deposit, and forcibly expelling from said material a large proportion of said liquid of saturation, maintaining said material in such condition free from the modifying action of other fluid for a period sufficient to 10 permit the weakened action on the material of the said treating liquid remaining therein, and then subjecting said material to a washing operation upon the termination of 15 the action of said remaining liquid thereon.
2. That method of continuously conditioning textile material in lengths which consists in progressing the material with the same end always foremost and subjecting it during said progress to a washing action, then depositing a mass of said material in successive folds and substantially saturating it with a treating liquid, then withdrawing 20 said folds from said mass in their order of deposit, and forcibly expelling from said material a large proportion of said liquid of saturation, maintaining said material in such condition free from the modifying action of other fluid for a period sufficient to 25 permit the weakened action on the material of the said treating liquid remaining therein, and accumulating it in a mass depending in amount and period of accumulation upon the speed of the subsequent operations, and 30 then terminating the action of said remaining treating liquid by subjecting the material to the action of a neutralizing liquid.
3. That method of continuously conditioning textile material in lengths which 35 consists in progressing the material with the same end always foremost and during said progress depositing a mass thereof in successive folds and substantially saturating it with a treating liquid, then withdrawing 40 said folds from said mass in their order of deposit, and forcibly expelling from said material a large proportion of said treating liquid of saturation, then depositing the material by gravity in loose folds, and maintaining said material in that condition in which it was placed by the expelling of said 45 large proportion of treating liquid and free from the modifying action of other fluid, thereby to permit the weakened action on 50 said material of the treating liquid remaining therein, whereby said treating liquid may be permitted to exhaust its strength upon said material.
4. That method of continuously conditioning textile material in lengths which 55 consists in progressing the material with the same end always foremost and during said progress depositing a mass thereof in successive folds and substantially saturating it with a treating liquid, then withdrawing 60 said folds from said mass in their order of deposit, and forcibly expelling from said material a large proportion of said treating liquid of saturation, then depositing the material by gravity in loose folds, and maintaining said material in that condition in which it was placed by the expelling of said 65 large proportion of treating liquid and free from the modifying action of other fluid, thereby to permit the weakened action on said material of the treating liquid remaining therein, whereby said treating liquid may be permitted to exhaust its strength upon said material.

consists in progressing the material with the same end always foremost and during said progress depositing a mass thereof in successive folds and substantially saturating it with a treating liquid, then withdrawing 70 said folds from said mass in their order of deposit, and forcibly expelling from said material a large proportion of said liquid of saturation, then depositing the material by gravity in loose folds, and maintaining said material in that condition in which it was placed by the expelling of said large proportion of treating liquid and free from the modifying action of other fluid, thereby to permit the weakened action on said material of the treating liquid remaining 75 therein, and terminating the action of said remaining liquid upon said material by subjecting said material to the action of a neutralizing liquid.

5. That method of continuously conditioning textile material in lengths which consists in progressing the material with the same end always foremost and subjecting it during said progress to a washing action, then depositing a mass of said material in successive folds and substantially saturating it with a treating liquid, then withdrawing 80 said folds from said mass in their order of deposit and bringing said material under the influence of normal atmospheric action and forcibly expelling from said material a large proportion of said liquid of saturation, depositing the material by gravity in loose folds and maintaining said material in that condition in which it was placed by the expelling of said large proportion of treating liquid and free from the modifying action of other fluid, thereby to permit the weakened action on said material of the treating liquid remaining 85 therein, and whereby said treating liquid may be permitted to exhaust its strength upon said material.

6. That method of continuously conditioning textile material in lengths which consists in progressing the material with the same end always foremost and subjecting it during said progress to a washing action, then depositing a mass of said material in successive folds and substantially saturating it with a treating liquid, then withdrawing 90 said folds from said mass in their order of deposit and forcibly expelling from said material a large proportion of said liquid of saturation, maintaining said material in such condition free from the modifying action of other fluid until the treating liquid remaining in the material has been permitted substantially to 95 exhaust its strength, and then subjecting said material to a washing action upon the termination of the action of said treating liquid.

7. That method of continuously condi-

tioning textile material in lengths which consists in progressing the material with the same end always foremost and subjecting it during said progress to a washing action, then depositing a mass of said material in successive folds and substantially saturating it with a treating liquid, then withdrawing said folds from said mass in their order of deposit and forcibly expelling from said material a large proportion of said liquid of saturation, maintaining said material in such condition free from the modifying action of other fluid until the treating liquid remaining in the material has been permitted substantially to exhaust its strength, subjecting said material to a washing action upon the termination of the action of said treating liquor, and then subjecting said material to a souring action.

8 That method of continuously conditioning textile material in lengths which consists in progressing the material with the same ends always foremost and subjecting it during said progress to a washing action, then depositing a mass of said material in successive folds and substantially saturating it with a treating liquid, then withdrawing said folds from said mass in their order of deposit and forcibly expelling from said material a large proportion of said liquid of saturation, maintaining said material in such condition free from the modifying action of other fluid until the treating liquid remaining in the material has been permitted substantially to exhaust its strength, subjecting said material to a washing action upon the termination of the action of said treating liquor, then subjecting the material to a souring action, and then subjecting said material to

a final washing, all of said steps constituting a continuous conditioning process.

9. That method of continuously conditioning textile material in lengths, which 45 consists in progressing the material with the same end always foremost and subjecting it during said continuous progress to a washing action, then depositing a mass of said material in successive folds, and subjecting it to the action of a treating liquid, then withdrawing said folds from said mass in their order of deposit, and then subjecting said material successively to a washing, a souring and then a final washing 50 action, the material being subjected to all of said steps while being continuously progressed with the same end always foremost.

10. That method of continuously conditioning rope-form, textile material in 60 lengths, which consists in progressing the material with the same end always foremost, and subjecting it during said continuous progress to a washing action, then depositing a mass of said material in successive, laterally-traversed folds and subjecting it to the action of a treating liquid, then withdrawing said folds from said mass in their order of deposit, and then subjecting said material to a washing, a souring 65 and then a final washing action in laterally-traversed folds, the material being subjected to all of said steps while being continuously progressed with the same end always foremost.

In testimony whereof I have signed my name to this specification, in the presence of two subscribing witnesses.

ISAAC E. PALMER.
